UNITED STATES PATENT OFFICE.

MORRIS F. ELDRIDGE, OF TOLEDO, OHIO.

CARRIAGE-TOP.

SPECIFICATION forming part of Letters Patent No. 372,367, dated November 1, 1887.

Application filed February 14, 1887. Serial No. 227,754. (No model.)

To all whom it may concern:

Be it known that I, MORRIS F. ELDRIDGE, a citizen of the United States, residing at Toledo, in the county of Lucas and State of Ohio, have 5 invented new and useful Improvements in Carriage Tops, of which the following is a specification.

My invention relates to improvements in carriage-tops, such as are designed to be let 10 down and put up when desired, constructed of bows and held in position by jointed brace- rods attached to the top of the seat, and pro- vided with an outside covering and an inside 15 lining; and the objects of my improvements are to provide a simple, cheap, durable, and easily-operated device to support the up- 20 per portion of the front bow, so that the lower portion of the front bow may be taken away to make it convenient to get in and out 25 of the ordinary top-carriage, and to make this support so that it folds up easily with the letting down of the top. I attain these objects by the mechanism illustrated in the accom- 30 panying drawings, in which—

Figure 1 is a side elevation of a carriage bed and top with my device attached to it, showing the top up and down. Fig. 2 is a 35 group of views showing the triple-jointed hinge-support, right and left, opened and closed.

Similar letters refer to similar parts throughout the several views.

A is an ordinary carriage-bed.

B is an ordinary carriage-top, consisting of 40 its various parts, the bows *b b b*, jointed brace or stay rods *C* and *D*, the covering *e e*, the lining *f*, and the brace pivot-posts *d d*, all arranged substantially after the manner and in accordance with the present style of the 45 construction of carriage-tops.

My invention consists in the taking away of the lower portion of the front bow, *k*, on each side, (represented by dotted lines,) and supporting the remaining upper portion of 50 the front bow and operating it by a triple-jointed bracket-hinge, *H' H²*, made right and left to suit each side of the top, in which hinge No. 1 is secured to the center bow sub- stantially by means of screws, bolts, or rivets.

Hinge No. 3 is secured by screws, rivets, or 55 bolts to the front bow, and hinge No. 2—the

center one—is a raised hinge, which folds in- 60 ward and retains the plates at a sufficient distance from each other to allow the leather or other material of the cover to fold be- 55 tween them and not be cramped short, so as to injure it in use; also, I is a ribbon of steel or a strong and substantial piece of webbing or girth, which is secured to the back bow at one end and passes under a loop, *i*, on the 65 center bow, through the openings in the plates of the bracket-hinge *H*, thus passing around the center hinge, No. 2, as shown in center view of group, Fig. 2, the other end of which is secured to the front bow, the whole being 70 made firm when the top is up in position for use. By means of this stay I great stiffness and firmness are given to the center hinge, No. 2, of the bracket *H*, in which construction and operation I get the combined action of the 75 jointed brace or stay rods *C* and *D* to sup- port this triple-jointed bracket-hinge *H* and the front bow of the top *B*. When the top is down, it assumes the position shown also in the right of Fig. 1 connected by broken lines. 75

In some cases, for the sake of cheapness, I design to do away with the front jointed stay- 80 rod, *D*, and when I want the front and back sections of the top to work independent of each other the ribbon or webbing *I* is fastened se- 85 curely on the center bow, and in case a ribbon of steel is used it is covered to prevent its chafing the other parts.

In the construction of the triple-jointed bracket-hinges *H' H²*, I design to have the 85 hinges separate and secure them to the plates, or have them cast solid on the plates. The front bow from the ends up around the curves is plated in a substantial manner to prevent 90 it from straightening by use and the action 95 of the atmosphere. In the finished top these parts of my invention are concealed between the covering *e e* and the lining *f*. The side curtains may be cut as at present, so as to ex- 100 tend in front from the end of the front bow in the direction of the dotted lines to the pivot on the side of the seat, and when desired may be folded back on the inside and buttoned at the top, leaving the desired part of the side clear.

Having described my invention and its re- 100 lation to the present construction of carriage-

tops, what I claim as my invention, and desire to secure by Letters Patent, is—

In a carriage-top support, the combination, with the bows b b b and jointed stay-rod C , of the open brackets H' H'' , hinged to the bows b b b and together by a raised hinge, and the stay I and loop i , all substantially as described and set forth.

In testimony whereof I have hereunto set my hand in the presence of two subscribing to witnesses.

MORRIS F. ELDRIDGE.
